UNITED STATES PATENT OFFICE.

THOMAS RHODUS, OF CHICAGO, ILLINOIS, ASSIGNOR TO THE MAGNIPHONE COMPANY,
A CORPORATION OF ARIZONA.

TELEPHONE-RECEIVER.

1,166,152.

Specification of Letters Patent. Patented Dec. 28. 1915.

Application filed February 15, 1915. Serial No. 8,194.

To all whom it may concern:

Be it known that I, THOMAS RHODUS, a citizen of the United States of America, and a resident of Chicago, in the county of Cook and State of Illinois, have invented certain new and useful Improvements in Telephone-receivers, of which the following is a specification.

This invention relates more particularly to that type of telephone receivers having a compact, flat and light structural adaptation of parts, whereby the same can be supported in proximity to the ear of the user in a ready and convenient manner.

15 And the present improvement has for its various objects: 1. To provide a light and efficient formation and arrangement of parts of the electro-magnetic member of the receiver adapted to afford a simple and compact association with the inclosing shell or casing with an ample yet compact structure of the helix or winding or insulated wire of said electro-magnetic member. 2. To provide a simple, efficient and convenient formation and arrangement of terminal plates of the receiver, whereby said plates are adapted for ready connection with the line wire terminals, with the switch of the receiver and with the respective ends of the 25 energizing coil or helix of the electro-magnetic member, without encroachment upon the central sound cavity of the receiver. 3. To provide a simple and efficient construction of local switch within the receiver, 30 adapted to afford a ready and effective switching function without encroaching upon the central cavity of the receiver. 4. To provide an efficient formation and adaptation of the central adjustable pole piece 40 of the electro-magnetic member of the receiver, adapting this same for ready attachment to a supporting head band or yoke, without interference with the manual adjustment of said pole piece. 5. To provide 45 an efficient arrangement and combination of parts, in which the manual adjustment of the central pole piece or core of the electro-magnetic member of the receiver can be readily effected, and with which said pole piece or core is held from independent local vibration or movement in its support; all as will hereinafter more fully appear.

In the accompanying drawings: Figure 1, is an elevation of the present telephone receiver, the ear piece or cap and the dia-

phragm being removed. Fig. 2, is a transverse section on line $x-x$, Fig. 1. Fig. 3, is a detail transverse section on line $x'-x'$, Fig. 1. Fig. 4, is a detail sectional view on line x^2-x^2 , Fig. 3. Fig. 5, is a detail transverse section on line x^3-x^3 , Fig. 1. Fig. 6, is a detail perspective view of an end portion of the supporting head band or yoke by which the receiver is supported in proximity to the ear of the user. Fig. 7, is a perspective view of the parts in a detached condition.

Similar reference numerals indicate like parts in the several views.

Referring to the drawings, 1 represents the containing shell or housing of the receiver, and comprising a bottom web 2, and an annular wall 3, the upper end of which is externally screw-threaded for engagement with a correspondingly formed marginal rim of the cap or ear piece 4 of the receiver. In the construction shown the aforesaid bottom web 2 is formed with a central orifice 5 for the passage of the adjusting end of the hereinafter described central core or pole piece of the electro-magnetic member of the receiver, and with a pair of interior ledges or posts 6, for the attachment of said electro-magnetic member and its accessories.

7 designates the diaphragm of iron or other suitable material, and held in place in any suitable manner, usually by its marginal portion engaged between the top rim of the wall 3 of the receiver housing and a companion annular rib 8 in the interior of the cap or ear piece 4, aforesaid.

9 designates the base plate or piece of the electro-magnetic member, formed preferably, of a flat disk of metal provided with peripheral attaching ears or lugs 10, and with a central screw-threaded orifice for holding engagement with a correspondingly formed portion of the adjustable central core or pole piece hereinafter described.

11 designates the annular or outer pole piece of the above mentioned electro-magnetic member, and comprising a narrow marginal rim 12, having attaching ears or lugs 13 corresponding with the ears or lugs 10, of the base piece 9, aforesaid, and a cone-shaped inner web 14 having a central orifice for the reception of one end of the hereinafter described spool or bobbin upon which is wound the coil or helix of the electro-magnetic mem-

ber. In the present construction said cone-shaped web 14 is formed with a pair of orifices provided with insulating bushings 15, through which the lead wires to the coil or helix pass, as hereinafter more fully described.

16 designates the spool or bobbin above referred to, having a length corresponding with the distance between the aforesaid base 10 plate 9 and the remote portion of the inner web 14, as shown. In its preferred form shown in Fig. 2, the spool or bobbin 16 has an outer rim 17 of a small diameter fitting the central orifice of the aforesaid annular pole piece 11, and with an inner rim 18 of a large diameter and resting against and secured to the base piece 9, aforesaid. As so formed the spool or bobbin is adapted to hold the conically wound energizing coil or 20 helix 19 of the electro-magnetic member, and provide a maximum length and energizing efficiency in said coil or helix.

20 designates the cylindrical central core or pole piece of the electro-magnetic member, extending through the axial bore of the spool or bobbin 16, aforesaid. Said pole piece 20 is formed with a threaded-portion 21 intermediate of its length for operative engagement with the screw-threaded central orifice of the base plate 9 aforesaid, and with a reduced neck extending from said portion 21, and carrying an operating head or handle 22, which in the present improvement is formed with a peripherally grooved 30 collar 23 adapted for holding engagement with a receiving orifice 24, of a key-hole form, in the end of a holding band 25 of an ordinary head gear by which the receiver is held in position adjacent to the ear of the 40 user. The described construction is adapted to permit of the ready manual turning of the pole piece 20, in effecting the usual adjustment of the same to and from the diaphragm 7, to vary the degree of vibration of the same as usual in the present class 45 of telephone receivers.

26 designates a coiled spring surrounding the reduced neck of the pole piece 20, and interposed between the base plate 9 and collar 23, before described. The purpose of the spring is to exert a yielding longitudinal stress upon the pole piece 20 and hold its screw-threaded portion 21 in close contact with the screw-threads of the central orifice 55 of the base plate 9 aforesaid.

27 and 28 designate the pair of terminal plates of the receiver. In the present construction said plates are of the segmental or curved form shown in Figs. 1 and 7 and 60 secured in an insulated manner upon the marginal ears 13 of the annular pole piece 11, by screws 29 and an interposed plate 30 of insulating material and of a curved shape corresponding with that of the terminal plates 27, 28, aforesaid. The screws 29 pass

down through the marginal ears 13, aforesaid, and screw into the companion ears 10 of the base plate 9, and are adapted to hold the various parts in an assembled condition.

31 designates an attaching screw passing 70 down through the middle portion of the terminal plate 27 and the insulating plate 30 and screwing into one of the ledges 6 of the housing 1, to form a part of the detachable connection between said housing 1 and the 75 electro-magnetic member and its accessories above described.

32 designates a companion attaching screw, which in this instance is of the ordinary insulated type, and passes between adjacent ends of the terminal plates 27, 28, and screws into the other ledge 6 of the housing 1, to constitute the other part of the detachable connection above described in connection with the attaching screw 31.

33 and 34 designate tubular eyes or enlargements formed on the adjacent ends of the terminal plates 27, 28, opposite to the adjacent ends above mentioned, and adapted to receive the terminal plugs or pins 35 of the live wires. In the preferred form of the present invention the terminal plate 27, aforesaid, is formed in two portions or sections, arranged in spaced and insulated relation, with the end of one section having a 90 curved formation 36, as shown on Figs. 5 and 7, to constitute a spring contact bearing for the point of the switch member, now to be described.

37 designates an approximately semi-circular switch member of a plate form, pivoted at one end to a stationary post 38 disposed between the pair of tubular eyes 33, 34, aforesaid. Said switch member extends around over one section of the terminal plate 90 27 into adjacent relation to the curved end formation 36, of the other section of said terminal plate 27, and adapted to be manually moved into electrical contact therewith when required. Near its free end, the switch 105 member 37, is deflected downwardly to be in electrical contact with the section of the terminal plate 27 first above mentioned, and is provided with a lateral handle 39, extending through a slot in the cylindrical wall 3 110 of the housing 1 for convenient manual operation.

40 designates a knob or rib formed on the terminal plate 27 and disposed in advance of the contact end of the switch member 37, 120 and adapted to provide a barrier against free or accidental shifting of the switch member from the position at which it may be placed.

41 and 42 designate conducting wires extending 125 from the terminal plates 27, 28, through the insulating bushings 15 of the annular pole piece 11 and connecting the respective ends of the coil or helix 19 with said terminal plates.

Having thus fully described my said invention what I claim as new and desire to secure by Letters Patent, is:—

1. In a telephone receiver, the combination of a housing, a diaphragm carried by said housing, an electro-magnetic member comprising a central pole piece, an energizing coil surrounding said pole piece, a base plate carrying said central pole piece and an annular pole piece having a cone form with its base in contact with the base plate, and terminal means, substantially as set forth.

2. In a telephone receiver, the combination of a housing, a diaphragm carried by said housing, an electro-magnetic member comprising a central pole piece, an energizing coil surrounding said pole piece, a base plate carrying said central pole piece and an annular pole piece having a cone form and provided with a marginal contact flange, said flange having connection with said base plate, and terminal means, substantially as set forth.

3. In a telephone receiver, the combination of a housing, a diaphragm carried by said housing, an electro-magnetic member comprising a central pole piece, an energizing coil surrounding said pole piece, a base plate carrying said central pole piece and having a marginal recess, an annular pole piece having a cone form and provided with a marginal contact flange, and terminal means substantially as described.

4. In a telephone receiver, the combination of a housing, a diaphragm carried by said housing, an electro-magnetic member comprising a central pole piece, an energizing coil surrounding said pole piece, a base plate carrying said central pole piece and an annular pole piece having a cone form and provided with a marginal contact flange having a recess in its circumference said flange having connection with said base plate, and terminal means, substantially as set forth.

5. In a telephone receiver, the combination of a housing, a diaphragm carried by said housing, an electro-magnetic member comprising a central pole piece, an energizing coil surrounding said pole piece, an annular pole piece having a cone form and provided with marginal ears, a base plate having marginal ears and a central orifice for connection with the central pole piece, segmental terminal plates, an interposed insulating plate, and screws passing through said terminal plates, insulating plate and marginal ears to secure the parts in assembled relation, substantially as set forth.

6. In a telephone receiver, the combination of a housing, a diaphragm carried by said housing, an electro-magnetic member comprising a central pole piece, an energizing coil surrounding said pole piece, an annular pole piece having a cone form and

provided with marginal ears and a pair of insulated bushings in its cone shaped web, a base plate having marginal ears and a central orifice for connection with the central pole piece, segmental terminal plates, an interposed insulating plate, screws passing through said terminal plates, insulating plate and marginal ears to secure the parts in assembled relation, and connecting wires between the terminal plates and the energizing coil passing through the insulating bushings of the annular pole piece, substantially as set forth.

7. In a telephone receiver, the combination of a housing having a plurality of interior ledges, a diaphragm carried by said housing, an electro-magnetic member comprising a central pole piece, a coil surrounding said pole piece, an annular pole piece having a cone form and provided with marginal ears, a base plate having marginal ears and a central orifice for connection with the central pole piece, segmental terminal plates, an interposed insulating plate, screws passing through said terminal plates, insulating plate and marginal ears to secure the parts in assembled relation, and screws passing through the terminal plates and screwing into the ledges of the housing, substantially as set forth.

8. In a telephone receiver, the combination of a housing, a diaphragm carried by said housing, an electro-magnetic member comprising a central pole piece, an energizing coil surrounding said pole piece and having a conical form, a bobbin carrying said coil and end rims of different diameters, an annular pole piece having a cone form and marginal ears, a base plate having marginal ears and a central orifice for connection with the central pole piece, segmental terminal plates, an interposed insulating plate, and screws passing through said terminal plates, insulating plate and marginal ears to secure the parts in assembled relation, substantially as set forth.

9. In a telephone receiver, the combination of a housing, a diaphragm carried by said housing, an electro-magnetic member comprising a central pole piece, an energizing coil surrounding said pole piece, an annular pole piece having a cone form and provided with marginal ears a base plate having marginal ears and a central orifice for connection with the central pole piece, a pair of terminal plates one of which is formed in two sections, a swinging semi-circular switch member having constant contact with one of said sections and adapted to be moved into contact with the other of said sections, an interposed insulating plate, and means for attaching the parts in assembled relation, substantially as set forth.

10. In a telephone receiver, the combina-

- tion of a housing, a diaphragm carried by said housing, an electro-magnetic member comprising a central pole piece, an energizing coil surrounding said pole piece, an annular pole piece having a cone form and provided with marginal ears, a base plate having marginal ears and a central orifice for connection with the central pole piece, a pair of terminal plates one of which is formed in two sections, a swinging semi-circular switch member having constant contact with one of said sections and adapted to be moved into contact with the other of said sections, an interposed insulating plate, and means for securing the parts in assembled relation, one of said terminal plate sections having a barrier projection disposed in the path of the switch member, substantially as set forth.
- 10 11. In a telephone receiver, the combination of a housing, a diaphragm carried by said housing, an electro-magnetic member comprising a central pole piece having an intermediate screw-threaded portion and an operating handle at one end, an energizing coil surrounding said pole piece, an annular pole piece, a base plate connecting said pole pieces and having a central screw-threaded orifice for the adjustable engagement of the screw-threaded portion of the central pole piece, and means for securing the base plate to the annular pole piece, substantially as set forth.
- 15 12. In a telephone receiver, the combination of a housing, a diaphragm carried by said housing, an electro-magnetic member comprising a central pole piece having an intermediate screw-threaded portion and an operating handle at one end, said handle having a peripherally grooved collar for holding engagement with a head band, an energizing coil surrounding said central pole piece, an annular pole piece, a base
- plate connecting said pole pieces and having a central screw-threaded orifice for the adjustable engagement of the screw-threaded portion of the central pole piece, and means for securing the base plate to the annular pole piece, substantially as set forth.
- 20 13. In a telephone receiver, the combination of a housing, a diaphragm carried by said housing, an electro-magnetic member comprising a central pole piece, an energizing coil surrounding said pole piece, an annular pole piece having a cone form and provided with marginal ears, a base plate having marginal ears and a central orifice for connection with the central pole piece, segmental terminal plates having tubular enlargements at their adjacent ends for the reception of terminal pins of the line wires, an interposed insulating plate, and means for securing the parts together in assembled relation, substantially as set forth.
- 25 14. In a telephone receiver, the combination of a housing, a diaphragm carried by said housing, an electro-magnetic member comprising a central pole piece having an intermediate screw-threaded portion and an operating handle at one end, an energizing coil surrounding said pole piece, an annular pole piece, a base plate connecting said pole pieces and having a central screw-threaded orifice for the adjustable engagement of the screw-threaded portion of the central pole piece, means for securing the base plate to the annular pole piece, and a coiled spring interposed between the base plate and the operating handle of the central pole piece, substantially as set forth.
